UNITED STATES PATENT OFFICE

EUGENE F. MARTINET, OF CLEVELAND, OHIO, ASSIGNOR TO THE DUAL SPEEDOMETER COMPANY, OF CLEVELAND, OHIO, A CORPORATION OF OHIO

SPEED-INDICATING CONTROL MEANS

Application filed February 13, 1929. Serial No. 339,525.

Speed indicating devices as employed with vehicles, such as motorcycles or automobiles are encased in a suitable housing which requires mounting in as favorable position as is 5 possible, consistent with protection and visibility. With indicating devices having an indexing means requiring a manual control, such mounting is at the best quite awkward for the operator, and necessitates excessive 10 movement and attention. Particularly in the case of traffic officers employing a precision speedometer to register the travelling rate of a traffic speed violator, it is highly desirable that the instrument be capable of control with 15 a minimum of arm-movement and diversion of attention.

To the accomplishment of the foregoing and related ends, the invention, then, consists of the features hereinafter fully described, 20 and particularly pointed out in the claims, the following description and the annexed drawing setting forth in detail certain structure embodying the invention, such being illustrative however of but one of the various ways 25 in which the principle of the invention may be employed.

In said annexed drawing:—

Fig. 1 is a broken perspective view of an embodiment of the invention, parts being 30 crowded together on account of space limitation in the drawing; Fig. 2 is a detail of the lower side of an instrument casing, showing the control connection; Figs. 3 and 4 are details; and Fig. 5 is a detail of a modified 35 form.

In its general aspects, the invention contemplates a speed-indicating means mounted on any usual or convenient point of the frame or dash of the vehicle, and a remote-control 40 means therefor directly accessible to the operator's hand.

As illustrated in the drawing, a casing 2 contains translating mechanism of any preferred type, centrifugal, electromagnetic, 45 etc., for translating the motion from the vehicle wheel through the customary connection, whereby a visible indicator shows the speed rate. For the purposes of illustration, there is shown a running hand 3 which indicates the running speed at all times, and a 50

maximum hand 4 which is pushed along by such running hand, by an interengaging lug, and a stop hand 5 which normally travels along with and over the running hand, but which when desired may be disengaged therefrom so as to stationarily furnish a showing of the speed rate at the instant of disengagement. Suitable means are provided for the release of the maximum hand for resetting, the detail being immaterial to the present invention. Means are also provided for the control of the engagement and disengagement of the stop hand. Whether the stop hand be a running hand capable of being disengaged from the driving spindle as desired, or a separate stop hand to ride over the running hand as specifically illustrated, is immaterial as regards the general control features. With a disengaging means of suitable construction, the detail of which may of course vary, and which for the present purpose may be indicated as a lifter fork arm 6 raised and lowered by a cam 7, a suitable throw lever 8 externally of the casing makes connection to the operating cam through a rock shaft 9.

Attached to the throw lever 8 is a push-pull element 10, preferably a wire carried through a suitable guide, as an armored conduit or the like 11 to a convenient point of control-actuation by the operator. This should be within 80 convenient range of the operator's hand as normally employed with the steering control. Whether a steering wheel as in an automobile or a steering handle as in a motorcycle, the principle is of course the same, and the control-button 12 is by preference mounted directly upon the steering member, the mounting desirably being of adjustable type so as to accommodate to the particular requirements of right handed or left handed operators. 85 The control-button may be on a lever 13 of bell crank type, the other arm 14 whereof is connected to the push-pull element 10.

In the form shown in Fig. 5, the control-button embodies a thumb-piece 22 on a lever 95 13' which is pivoted at *p* on a plate secured to the handle bar or steering wheel, and the other arm 14' of the bell-crank lever is connected to the push-pull wire 10.

In operation, the running hand 3 will at 100

all times indicate the actual speed, and the maximum hand 4 as pushed along by the running hand and retained by customary means will indicate the maximum attained. 5 With the stop hand 5 in engagement over the running hand 3, such two hands move together and correspondingly show the running speed. When it is desired however to retain a showing of the running speed at any 10 particular instant, the operator manipulates the control-button 12 or 22 to throw the lever 8 into position to raise the stop hand from engagement with the running hand and retain the record showing at such instant. The 15 position of such stop hand will of course be maintained until it be released to again engage with the driving mechanism; and when the purposes for which the record registry was employed are completed, the reverse movement of the control-button 12' by the operator throws the lever 8 to engage the stop hand 5 with the running hand, whereupon it again travels in consonance therewith.

As will be seen, the mobile or flexible character of the connecting means between the operator's control-button and the indicating instrument allows of the utilization of most convenient locations for each particular part; and with the control-button directly on the 20 steering means, the operator is enabled to engage and disengage the indexing element with its drive at will, and without necessitating removal of the hand from the steering control or requiring diversion of attention. For 25 traffic usage in particular, a degree of convenience is thus obtained making possible a maximum of accuracy in traffic checking and with the utmost convenience to the operator.

Other modes of applying the principle of 30 the invention may be employed, change being made as regards the details disclosed, provided the means stated in any of the following claims, or the equivalent of such, be employed.

45 I therefore particularly point out and distinctly claim as my invention:—

1. Apparatus of the character described, which comprises a speed indicating means, means other than the prime mover for starting and stopping said indicating means, and remote-control means for operating said starting and stopping means.

50 2. Apparatus of the character described, which comprises a speed index, means for connecting and disconnecting said index to the drive, and remote-control means for operating said connecting and disconnecting means.

55 3. Apparatus of the character described, which comprises a speed indicating means, a control-button adapted to be located adjacent to vehicle steering means, means other than the prime mover for starting and stopping said speed indicating means, and a flex-

ible connection between said control-button and said steering and stopping means.

4. Apparatus of the character described, which comprises a speed index, a control-button adapted to be located adjacent to vehicle steering means, means for connecting and disconnecting said speed index to the drive, and a flexible connection between said control-button and said connecting and disconnecting means.

5. Apparatus of the character described, which comprises a running hand, another hand engageable to be also driven, and remote-control means for engaging or disengaging said other hand.

6. Apparatus of the character described, which comprises a running hand, a maximum indicating hand pushed by said running hand, a stop hand engageable over said running hand, and remote-control means for engaging or disengaging said stop hand.

7. Apparatus of the character described, which comprises a running hand, a stop hand engageable therewith, a control-button adapted to be located adjacent to vehicle steering means, means for starting and stopping said stop hand, and a flexible connection between said control-button and said starting and stopping means.

8. Apparatus of the character described, which comprises a speed indexing means, a lever for engaging or disengaging said indexing means with drive means, a control-button, a push-pull wire connecting said control button with said lever, and means for guiding said wire.

9. Apparatus of the character described, which comprises a running hand, a stop hand engageable therewith, a lever for engaging or disengaging said stop hand with the running hand, a control-button, a push-pull wire connecting said control-button with said lever, and means for guiding said wire.

10. Apparatus of the character described, which comprises a running hand, a maximum indicating hand pushed by said running hand, a stop hand engageable over said running hand, a lever for engaging or disengaging said stop hand with said running hand, a control button remote from said lever, and a flexible connection between said control-button and said lever.

11. Apparatus of the character described, which comprises a running hand, a maximum indicating hand pushed thereby, a stop hand engageable over said running hand, a lever for engaging or disengaging said stop hand with the running hand, a control-button adapted to be positioned adjacent vehicle steering means, a flexible connection between said control-button and said lever, and means for guiding said flexible connection.

12. Apparatus of the character described, which comprises a running hand, a maximum indicating hand pushed thereby, a stop hand

engageable over said running hand, a lever
for engaging or disengaging said stop hand
with said running hand, a control-button
adapted to be positioned adjacent to vehicle
steering means, a push-pull wire connecting
said control-button with said lever, and a
conduit receiving said wire.

Signed by me this 7th day of February,
1929.
